UNITED STATES PATENT OFFICE.

ALBERT UNDERDAHL, OF CANNON FALLS, MINNESOTA.

GAS-TURBINE.

1,342,314.

Specification of Letters Patent.

Patented June 1, 1920.

Application filed January 5, 1918. Serial No. 210,480.

To all whom it may concern:

Be it known that I, ALBERT UNDERDAHL, a citizen of the United States, residing at Cannon Falls, in the county of Goodhue and 5 State of Minnesota, have invented certain new and useful Improvements in Gas-Turbines; and I do hereby declare the following to be a full, clear, and exact description of the invention, such as will enable others 10 skilled in the art to which it appertains to make and use the same.

This invention relates to rotary engines of the internal combustion type and has for its object to provide an engine including a 15 novel type of valve controlled combustion chamber from which the expanded gases subsequent to ignition are liberated and directed against the blades of a rotor.

Another object is the provision of means 20 for locking the valve in the combustion chamber in open position for a predetermined period subsequent to combustion so as to secure the maximum effect of the expanded gases upon the blades of the rotor. 25 Another object is the provision of an improved compressor for delivering the gaseous fuel to the combustion chamber under pressure.

With these and other objects in view, the 30 invention consists in the novel construction, combination and arrangement of parts as will be hereinafter specifically described, claimed and illustrated in the accompanying drawing, in which:

35 Fig. 1 represents a longitudinal sectional view through the turbine,

Fig. 2 represents an enlarged vertical sectional view through one of the rotor housings and combustion chambers,

40 Fig. 3 represents a detail sectional view on the line 3-3 of Fig. 2,

Fig. 4 represents an enlarged sectional view through the throttle valve governor,

45 Fig. 5 represents an end elevation of the turbine partly in section,

Fig. 6 represents a detail sectional view through the throttle valve, and

Fig. 7 is a perspective of the turbine.

Referring to the drawings in detail, 50 wherein similar reference numerals designate corresponding parts throughout the several views, the numeral 5 indicates generally the casing of the engine, which is divided centrally by a vertical partition 6 into rotor and gear housings 7 and 8, respectively. The rotor shaft 9 is journaled

in bearings 10 provided in the end wall of the rotor housing 7 and the partition 6 and the end of the rotor shaft, which projects within the chamber of the gear housing 8, is 60 provided with pinions 11, which mesh with gear wheels 12 secured upon the driven shaft 13. The shaft 13 is journaled in bearings 14 provided in the partition 6 and end wall of the gear housing 8 and also in an 65 intermediate bearing support 15 arranged upon the bottom of the gear housing 8.

The rotor housing 7 is preferably provided with a circumferential chamber 16 for the reception of water to assist in cooling 70 the engine during operation and the inner surface of the cylindrical wall of the housing is provided with a plurality of internal annular grooves 17 receiving the rims of the several rotors 18, which are secured to 75 and supported upon the rotor shaft 9.

A hollow cylinder 19 is formed on the top of the rotor housing 7 adjacent each internal groove 17 and communicates therewith by a restricted inlet port 20, which is 80 disposed at an angle to a radial plane through the rotor housing so as to direct the expanded gases against the blades 21 of the rotor so as to revolve the latter. The cylinders 19 are arranged in a horizontal position 85 and are provided intermediate their ends with internally threaded openings 22 to receive preferred types of spark plugs 22' by which the compressed charge is ignited.

The outer ends of the cylinders 19 are 90 closed by detachable caps or heads 23, and the inner terminals thereof are provided with valve seats 24 for receiving the valves 25, which latter are normally retained in closed position by the tension of springs 26 95 and 27. The outer terminal of each valve stem 28 is threaded in a reciprocating piston 29, and the space 30 between the valve 25 and the piston 29 constitutes the combustion chamber in which the explosion of the 100 combustible mixture occurs. The outer terminal of the piston is rigidly connected with a rod 31, received in a tubular guide 32 carried by the detachable head 23 and provided with a V-shaped recess 32' for engaging 105 the latch plate 34, by which the piston is retained in retracted position, so as to maintain the valve open. A guide plate 35 is interposed between the open end of the cylinder 19 and the head 23 and is arranged in 110 spaced relation to the latter so as to accommodate the latch plate 34, which latter is

normally retained in depressed position by the tension of a spring 36 coiled about a depending stem 37 carried thereby. The latch plate is provided with friction reducing 5 rollers 38 which bear against the guide plate 35 and the head 23, and the lower terminal of the stem is bifurcated to receive a roller 39, which bears upon a cam 40 secured to a cam shaft 41 underneath each cylinder 19. 10 The object of the cams 40 is to elevate the latch plate 34 against the tension of the springs 36 to release the pistons 29 to permit the latter to move forwardly to close the valve 25 under the influence of the several springs 26 and 27.

The piston 29 is provided intermediate its ends with a circumferential groove 42, which, when the valve 25 is in closed position, registers with the inlet port 43 in the lower part of each cylinder 19, whereby the explosive mixture is conducted from the elbow 44 to the groove 42. A spring actuated check valve 45 is arranged in the inner terminal of the elbow 44 to prevent back pressure in the latter, and the groove 42 communicates by a plurality of angular inlet ports 46 formed in the piston with the combustion chamber 30. When the valve 25 is in closed position, as illustrated in Fig. 2, the inner terminals of the inlet ports 46 communicate with the chamber 30, but when the piston is moved outwardly, as when an explosion occurs in the chamber 30, the inner terminals of the ports 46 are covered by the wall of the cylinder 19, thus closing the ports and preventing the explosion from leaking back into the inlet port 43. The piston 29, as will be understood, is of considerably greater diameter than the valve 25, so that the effect of the explosion in the combustion chamber 30 is to move the piston 29 outwardly and thus open the valve 25, permitting the expanded gases to discharge through the inlet port 20 and against 45 the blades 21 of the rotor associated with the cylinder in which the explosion occurs.

When the piston 29 is forced outwardly by the impact of the explosion in the chamber 30 it is locked in retracted position for a brief period by the latch plate 34, which drops into the recess 32 in the rod 31 and prevents the return movement of the piston and valve under the influence of the springs 26 and 27. The latch plate 34 is released or elevated to permit the piston and valve to assume their former position by the cam 40.

A cam shaft 41 is supported in bearings 41' secured to the rotor housing 7. One end of the shaft 41 is rotatably supported in the 60 governor housing 48, which is arranged laterally of the gear housing 8 and forms an inclosure for the bevel gear wheels 49, connecting the cam shaft 41 with the inclined drive shaft 50. The shaft 50 projects 65 through the side wall of the gear housing 8.

As indicated in Fig. 1 the reduced terminal 51 of the rotor shaft 9 terminates adjacent the lower end of the shaft 50 and is mounted in bearing 51' carried by the support 15. The reduced terminal of the rotor shaft and 70 the inclined shaft 50 are connected by bevel gear wheels 52, whereby the rotary movement of the rotor shaft is transmitted to the inclined shaft 50 to operate the cam shaft 41 during operation.

Each groove 17 in the rotor housing is provided with an outlet port 53, which is connected with the exhaust pipe 54 extending alongside of the housing 7 and extending to the inlet port 55 of the governor 80 housing 48. The governor housing 48 is provided at the end opposite the inlet port 55 with an outlet port 56, through which the exhaust products of combustion from the several rotors is discharged. A final exhaust 85 pipe 56' is connected to the port 56. Within the housing 48 a bladed wheel 57 is slidably and non-rotatably mounted upon the inclined shaft 50 and is normally retained in inwardly extended position toward the 90 driven shaft 13 by the tension of a spring 58, which is confined between the recessed hub 59 of the bladed wheel and the bearing 60 provided in the housing 48 for the shaft 50. The hub of the bladed wheel is provided with a tubular extension 61, having a flanged upper terminal providing a groove 62.

A double type of throttle valve 63 is arranged beneath the governor housing 48 and 100 includes an outer shell or housing 64 and a core 65 having a port 66 therethrough and inner and outer valves 67 and 68, respectively. The inner valve 67 is provided with a stem 69 carrying an arm 70, whereby the 105 valve may be conveniently adjusted by hand, and the two valves are separated by an annular partition 71. The outer valve 68 is provided with a hollow stem 72, carrying an arm 73 connected with the tubular extension 62 of the governor for automatically controlling the passage of the explosive mixture to the cylinders of the engine; the valve 63 is located in the pipe 75 at a point adjacent the end of the pipe that connects with 110 the reservoir, that will be hereinafter more fully described. From one side of the valve casing 64 the explosive mixture is conducted to the several elbows 44 of the cylinders 19 by the inlet pipe 75.

The arm 73 is connected to the throttle 62 of the governor through the medium of a link 73' and a bell crank 74'.

The top part of the gear housing 8 at the end opposite the rotor housing 7 is provided with a vertically disposed compression cylinder 76, in which a piston 77 is reciprocably mounted and is provided with a connecting rod 78. An eccentric strap 79 is connected with the lower terminal of 130

the rod 78 which embraces an eccentric 80 on the driven shaft 13, whereby a reciprocating motion is imparted to the piston 77 during rotation of the drive shaft 13. The 5 head of the cylinder 76 is provided with a valved inlet port 81 which is connected with a fuel supply pipe 81' by which gaseous fuel is conducted to the cylinder 76 from a carbureter 82'. The upper part of the cylinder 10 76 is connected with a tank or reservoir 82 by a pipe 83, and the reservoir 82 is designed to contain an adequate supply of gaseous fuel under pressure. A check valve 84 is arranged in the pipe connection 83 15 between the reservoir 82 and the cylinder 76 to prevent the compressed fuel from finding its way back into the head of the cylinder 76. A relief pipe 85 connects the lower portion of the reservoir 82 with the pipe 20 83 and pressure operated valves 86 are arranged in the pipe 85, which are adapted to be opened when the pressure of the gaseous fuel in the tank 82 reaches a predetermined value so as to cause the fuel to circulate back 25 and forth between the compressor cylinder and reservoir during reciprocation of the piston 77. The fuel supply pipe 75 for the several cylinders 19 is connected with the reservoir 82 and is connected with a T 30 shaped pipe 88 arranged within the reservoir. An angular nozzle 89 is arranged in the vertical portion of the T pipe 88; and the discharge end thereof is directed toward the supply pipe 75. The lower terminal of 35 the nozzle 89 communicates by a restricted opening with the lower portion of the reservoir 82, whereby any volatile fuel which condenses within the reservoir is conducted to the nozzle 89 which sprays it into the 40 pipe 75 in the form of vapor.

In operation, the gaseous fuel is conducted from the reservoir 82 to the pipe 75 through the throttle valve 63, again entering the pipe 75, elbows 44, grooves 42 and 45 inlet passages or ports 46 to the combustion chambers in the cylinders 19. The compression of the compressor cylinder forces the fuel through the reservoir 82 to the port 46. The charge in the combustion chamber of 50 each cylinder is ignited by the spark produced by the spark plug and the timing mechanism (not shown) for the ignition system is preferably so regulated as to cause the combustible mixture in the chambers 55 of the several cylinders to be successively ignited at predetermined periods. The impact of the explosion against the inner end of the piston 29 effects an outward movement of the latter which opens the valve 29, 60 permitting the expanding gases to discharge through the inlet port 25 and against the blades 21 of the rotor 18, thus rotating the latter. The valve 25 is locked in open position so as to obtain the maximum effect of

the expanding gases upon the rotor by the 65 latch plate 34, which is moved downwardly by the tension of the spring 36 when the piston 29 is moved outwardly. The piston and valve are subsequently released by the cam 40 of the cam shaft 41, which engages 70 the roller 39 of the latch plate, thus elevating the latter and disengaging it from the recess 32 in the piston-carried rod 31. During the operation of the engine the piston 75 77 is constantly reciprocated in the cylinder 76 and maintains the gaseous fuel in the tank or reservoir 82 at a predetermined pressure. The bladed wheel 57 operating in the housing 48 creates a vacuum in the exhaust pipe 54, eliminating back pressure 80 of the exhaust products of combustion in the rotor housing 7 and thoroughly scavenging the exhaust products of combustion. When the engine exceeds a predetermined speed, the atmospheric pressure upon the 85 blades of the wheel 57 forces the latter outwardly against the tension of the spring 58, thus shifting the lever 1 and actuating the arm 73 of the valve 68 to temporarily 90 cut off the supply of fuel to the several cylinders 19, or until the engine is again running at the proper speed.

What I claim is:

1. In an explosive engine, a housing, a rotor mounted in the housing, a cylinder 95 having an internal combustion chamber communicating at one end with the housing, said cylinder having an inlet port therein, a ported piston arranged in the cylinder normally connecting the inlet port with the 100 combustion chamber, and adapted to be actuated by the explosion occurring in the combustion chamber to close communication between the combustion chamber and the inlet port.

2. In a rotary engine, a rotor housing, a rotor journaled in the housing, said housing having inlet and exhaust ports therein, a combustion chamber communicating with the inlet port, an exhaust pipe connected with the exhaust port, a bladed wheel connected with the rotor for creating a vacuum in the exhaust pipe, and means controlled by the bladed wheel for controlling the admission of gaseous fuel to the inlet 115 ports.

3. In a rotary engine, a rotor housing, a rotor journaled in said housing, said housing having inlet and exhaust ports therein, a combustion chamber communicating with the inlet port, a fuel supply pipe connected with the combustion chamber, means for controlling the admission of gaseous fuel to the combustion chamber, a throttle valve connected with the supply pipe, an exhaust pipe connected with the exhaust port, a bladed wheel operatively connected with the rotor for creating a vacuum in the exhaust 120 125

pipe, and means connecting the bladed wheel with the throttle valve for controlling the latter.

4. In an explosion engine, a housing; a 5 rotor arranged within the housing; a cylinder having an internal combustion chamber therein; said housing having a passage extending from the cylinder to the rotor; said cylinder having an inlet port therein; 10 a piston arranged within the cylinder and adapted for a reciprocatory movement therein, said piston having a fuel supply channel extending to the combustion chamber and adapted to communicate with the 15 inlet port of the cylinder; and a valve connected with the piston and adapted to control the communication between the explosion chamber and the rotor.

5. In a rotary engine, a rotor housing,

a gear housing, said rotor housing having 20 inlet and outlet ports, a rotor journaled in the rotor housing, a governor housing mounted on the side of the gear housing, and an exhaust pipe connecting the exhaust port in the rotor housing with the governor 25 housing, a bladed wheel upwardly connected with the rotor for creating vacuum in the exhaust pipe, said bladed wheel located within the governor housing, and means associated with the bladed wheel to regulate 30 the speed of the engine.

In testimony whereof I affix my signature in presence of two witnesses.

ALBERT UNDERDAHL.
